UNITED STATES PATENT OFFICE.

ALBAN LEWIS GWINNNE, OF PORTSMOUTH, ENGLAND, ASSIGNOR TO VICKERS
LIMITED, OF WESTMINSTER, ENGLAND.

SUBMARINE MINE.

Application filed July 15, 1921. Serial No. 465,038.

(GRANTED UNDER THE PROVISIONS OF THE ACT OF MARCH 3, 1921, 41 STAT. L., 1313.)

To all whom it may concern:

Be it known that I, ALBAN LEWIS GWINNNE, commander R. N., a subject of the King of Great Britain, residing at H. M. S. "Vernon," Portsmouth, England, have invented certain new and useful Improvements in Submarine Mines, of which the following is a specification.

This invention relates to safety devices for preventing a premature explosion of a mine before it is properly placed in position, and consists in maintaining the primer and detonator out of the relative firing position, by mechanism which is operated by water pressure and requires a predetermined minimum force to effect the operation. The mechanism in a convenient form comprises a hydrostat or the like, the diaphragm of which is operatively connected to the primer or detonator as the case may be, and works against a spring to supply the minimum force to be overcome before the primer and detonator can take up the firing positions.

In order that the invention may be clearly understood and carried into effect the same will now be described more fully with reference to the accompanying drawings which illustrate in part sectional and broken elevation one form of the invention as applied to the firing gear of a submarine explosive body. Referring to the drawings primer 1 is mounted on a support 2 carried by a spindle 3, on which is mounted a sleeve 4, connected to a flexible member 5, which fulfills the function of a hydrostat diaphragm, the other end of which is fixed in any suitable way to a fixed part 6 of the mine. The sleeve 4 is initially locked to the spindle 3 by a ball releasing device such as is described in the specification for British Patent No. 8929/16, this form of ball release per se forming no part of this invention. The other end of the spindle is provided with a safety catch 7 or the like to prevent any accidental operation, this safety catch being moved to the off position when the mine is to be laid.

In operation, as the mine falls, the hydrostatic pressure lifts the sleeve 4 against the spring 8 until the ball 9 can pass away underneath the end 4' of the sleeve whereupon the hydrostatic pressure causes the flexible

member 5 to extend from its folding up position, as shown, thereby carrying the primer 55 up to the firing position relatively to the detonator 10, which initially is separated from the top of the primer 1 by the safe distance.

It will be seen that until the pressure is 60 sufficient to overcome the spring 8 of the ball releasing device to lift the sleeve 4 sufficiently for the ball to escape, the primer is unable to be moved towards the firing position.

It is of course obvious that the primer may be fixed and the detonator moved to the firing position in a similar manner to that above described.

What I claim and desire to secure by Letters Patent of the United States is:—

1. A submarine explosive body comprising a primer and detonator and means for maintaining said primer and detonator out of the relative firing position until after the 75 body has been launched.

2. A submarine explosive body comprising a primer and detonator and means for bringing the primer and detonator into the firing position after the body has been 80 launched and has reached a predetermined depth of submersion.

3. A submarine explosive body comprising a primer and detonator, means for exerting a minimum predetermined resistance 85 to relative movement of said primer and detonator and means which act, after the mine has been launched and reaches a predetermined depth of submersion, for causing said detonator and primer to assume the firing 90 position.

4. A submarine explosive body comprising a primer and detonator and hydrostatic means for maintaining said primer and detonator out of the relative firing position 95 until after the body has been launched.

5. A submarine explosive body comprising a primer and detonator and hydrostatic means for bringing the primer and detonator into the firing position after the body 100 has been launched and has reached a predetermined depth of submersion.

6. A submarine explosive body comprising a primer and detonator, a spring for exerting a minimum predetermined resistance to relative movement of said primer 105

and detonator, and hydrostatic means which act, after the mine has been launched, for causing said detonator and primer to assume the firing position.

5 7. A submarine explosive body comprising a primer and detonator, means, including a ball releasing device, for exerting a minimum predetermined resistance to relative movement of said primer and detonator, 10 and hydrostatic means which act after the body has been launched for causing said detonator and primer to assume the firing position.

8. A submarine explosive body comprising a primer and detonator, a movable support for said primer, a spindle connected to said support, a sleeve on said spindle, a spring positioned between said sleeve and said movable support, a fixed member on the

mine casing positioned between said sleeve 20 and said spindle, a ball releasing device, the balls of said releasing device being positioned within recesses in said fixed member and projecting within a recess in said spindle and being held in place by said 25 sleeve, and a diaphragm fulfilling the function of a hydrostat diaphragm, one end of which is connected to said sleeve and the other end to a fixed part of the explosive body.

9. In a submarine mine, in combination, a primer charge, a detonator in normal safety position remote from said primer charge with respect thereto and hydrostatically operative means adapted to produce 35 relative movement between said detonator and the primer charge.

ALBAN LEWIS GWYNNE.
